KNITTING MECHANISM

Edward Kinsella, John Gordon Pratt, and Bernard Kelsall, Spondon, near Derby, England, assignors to Celanese Corporation of America, a corporation of Delaware

Application October 26, 1932, Serial No. 639,637
In Great Britain November 3, 1931.

3 Claims. (Cl. 66—86)

This invention relates to the production of textile fabrics, and more particularly to the production of knitted fabrics on warp knitting machines.

5 The object of the invention is to improve warp knitting machines with the object of greatly increasing their rate of working and smoothness of operation, and rendering them capable of knitting fabrics of better and more uniform quality.

10 It has been found that a much improved rate of operation can be effected if the weight of the needle, sinker and guide bars and of like knitting parts can be reduced in proportion to the strength of such parts and their resistance against deflection.

15 According to the present invention the thread guides, needles, sinkers and like are secured to their bars by means of light fusible alloy of low specific gravity. Preferably the members are secured in series in a strip of such light alloy, 20 the strip being then fixed in position along the edge of the bar. Alternately the members may be secured in series to a steel or other light support by means of a light alloy, the steel support then being secured to the edge of the corresponding bar. A light alloy which is capable 25 of soldering itself to the needles and to the steel or like support if used is preferably employed, since this enables a relatively small amount of the alloy to be used, and so further reduces the 30 weight of the moving masses. A zinc-cadmium alloy is very suitable for this purpose.

The method of securing the knitting parts to their bars according to the invention greatly reduces the force necessary for the rapid movement of such parts, and, in consequence, the vibration resulting from such forces. Thus for example, it is necessary that the thread guides should be capable of making extremely rapid movements both in a direction endwise of the 35 machine and also between the needles. By adopting the light construction described above, the oscillatory guide movements in both directions can be effected with great rapidity, since the moving mass involved requires the minimum of applied force to involve reduced deflection and vibration.

In securing the sections of the guides, needles and the like to their bars, steps may be taken to ensure rigid connection. Thus for example, a pattern of parallel grooves may be effected on the side to which sections are to be secured, a corresponding pattern being formed on the sections also, e. g. cast into the light fusible metal applied so that the inter-engagement of the 50 grooves and ridges forms a very firm connection.

This is especially important in connection with the needles.

There are several light, readily-fusible alloys having sufficiently low melting points to enable them to be used for the purpose of the present 5 invention, for example, a zinc-aluminium alloy containing 95% zinc has a specific gravity of 6.3, an ultimate tensile strength of 6 tons per sq. in. and a melting point of 380° C., and a zinc-magnesium alloy containing 52% zinc has a specific 10 gravity of 4.6, an ultimate tensile strength of 6 tons per sq. in. and a melting point of 350° C. The lightness and strength of these alloys allow the needles, etc. to be rigidly secured in position while using quite a low weight of the fusible 15 metal.

It is preferred, therefore, to use a zinc-cadmium alloy which, while having a low specific gravity of 8.3, has a very high ultimate tensile strength of 10 tons per sq. in. so that in conjunction with 20 its ability to solder itself to the needles, etc. enables the needles, etc. to be secured firmly in place by means of a very small weight of alloy. The alloy having the low specific gravity and the high tensile strength given above contains a 25 slight excess of zinc over the 17.4% of zinc forming a eutectic mixture with cadmium, and also a minute proportion of chromium to refine the grain size, improve the surface obtainable, and increase the strength slightly. This alloy presents the further advantages of having a shear 30 strength of 8-8.5 tons per sq. in. and also the very low melting point of 263° C., which renders it particularly suitable for the purpose of the 35 present invention.

The invention may be employed with advantage in connection with the form of needle bar, sinker bar, and guide bars described in U. S. application S. No. 639,636 filed 26th October, 1932, and also with U. S. application S. No. 639,638 filed 26th October, 1932, which is concerned primarily with means for balancing the vibrational forces set up by the rapid motions of the knitting parts and thereby nullifying and greatly reducing 45 the effects of such vibrational forces on the machine frame.

The invention will now be described in greater detail with reference to the accompanying drawings, but it is to be understood that this description is given by way of example only and is in no respect limitative.

Figures 1 and 2 show a plan view and a sectional elevation of one form of guide section according to the present invention;

Figures 3 and 4 show similar views of another form of guide section;

Figures 5 and 6, and 7 and 8 respectively show two forms of sinker sections similar to the guide sections of Figures 1 and 2, and 3 and 4;

Figures 9 and 10 show two views of a needle section;

Figure 11 is a sectional view along the line 11—11 of Figure 9;

Figure 12 shows a view corresponding to Figure 9 of a smaller section of needles;

Figure 13 shows an assembled view in sectional elevation of the needle bar, sinker bar, presser bar and guide bars with the knitting parts attached; and

Figure 14 shows the needle bar in separate parts in order to illustrate the assembly.

Referring to Figures 1 and 2, the thread guides 17 are connected to a plate 18 of pressed sheet steel by means of a body of light but strong fusible alloy 20 which is cast round the guides 17 and the plate 18 when they are assembled in position. The sections illustrated in this and subsequent figures are on a large scale, the density 25 of spacing represented being of the order of 28 guides, sinkers or needles to the inch. It will be seen that the plate 18 is perforated as at 21 in order to ensure that the metal 20 should be securely bonded thereto. In addition it is preferable that the metal at 20 should be self soldering not only to the guides 17 but also to the metal of the plate 18, for which purpose a zinc-cadmium alloy is particularly suitable. The plate 18 is very light but rigid, so that in conjunction with the 35 small amount of the alloy required, the weight of the assembly is made very low. The whole guide section is adapted to be bolted onto the guide bar by means of a bolt passing through the hole 22 provided for the purpose, the several sections fitting closely against each other so as to be held rigidly to the bar, and forming a continuous series of closely spaced guides.

In Figures 3 and 4 the guides 17 are shown run into a casting 24 consisting wholly of light fusible metal, such as zinc-cadmium, the shape of the casting 24 being similar to that of the combined plate 18 and mass 20 illustrated in Figure 2. The slightly greater bulk of metal required may be wholly or in part off-set by using an alloy of light 45 specific gravity as compared with the steel of the plate 18. A hole 22 is formed in the casting 24 for the purpose of securing the sections of guides to the guide bar.

In Figure 5, the sinkers 27 are secured to a 55 member of pressed steel 28 by means of a body 29 of fusible metal as described with reference to Figures 1 and 2 in connection with the guides. Here also holes 21 are provided in the plate 28 for the secure bonding of the fusible metal 29 thereto, and a hole 22 is left for securing the sections of sinkers to the sinker bar. In addition the tips of the sinkers 27 are run into a body of fusible metal 30, the tips of the sinkers being of 60 hooked shape as indicated in Figure 6 in dotted lines at 31, thus ensuring that correct spacing of the sinkers during the knitting operation, e. g. 28 to the inch, is maintained. In Figures 7 and 8, the sinkers 27 are shown run into a casting 33, consisting wholly of fusible metal as in the case 65 of the casting 24 described in Figures 3 and 4, the shape of this casting being similar to that

of the plate 28 and body of fusible metal 29 described with reference to Figures 5 and 6. As in Figures 5 and 6 the hooked tips 31 of the guides are run into a body of fusible metal 30.

Figures 9, 10 and 11 show three views of a section of fourteen needles, (sufficient for, say, $\frac{1}{2}$ inch length of needle bar) the needles 35 being assembled in their correct spacing and run in with a body of metal 36. The metal 36 is provided with ridges 37 and upstanding areas 38 on 10 the one side, to fit into corresponding grooves on the face of the needle bar, so that the needles may be correctly positioned thereon. In addition, ridges 40 of metal are formed on the other side of the casting. In Figure 12 a small section 15 of three needles 35 is shown, having only one ridge 37 and one upstanding part 38 for positioning purposes.

Referring to Figure 13 it will be seen that the guide sections 41 are secured to the guide bars 20 20 by means of bolts 43 while the sinker sections 44 are attached to the sinker bar 45 by means of bolts 46. The needles 35 are secured in sections 47 to the needle bar 48 by means of clamping members 49.

The needle bar 48, needle sections 47 and clamping member 49 are shown apart in Figure 14, and it will be seen that vertical grooves 50 are provided in the recessed face of the needle bar 48 to correspond with the ridges 37 on the 30 needle sections, while a groove 51 extends horizontally along the whole length of the needle bar to accommodate the upstanding parts 38 of the needle sections, these means accurately locating the needles and enabling them to be secured in 35 correct position. The clamping member 49 is lined with felt at 52 into which the ridges 40 on the back of the needle sections sink, so that the needle sections may be securely clamped to the needle bar without being damaged.

In Figure 13 the rocker arms to which the guide bars 42, sinker bar 45 and needle bar 48 are secured are shown in chain dotted lines at 55, 56 and 57 respectively, while in this view also the presser bar 58 which carries the presser 59 and 45 50 is supported by the presser lever 60 are also shown in the relative positions they occupy in the warp knitting machine.

What we claim and desire to secure by Letters Patent is:—

1. Knitting elements for knitting machines secured in series by means of a zinc-cadmium alloy having a specific gravity not exceeding 8.3, and in which cadmium predominates.

2. A knitting element section for a knitting machine comprising a light metal support and a plurality of knitting elements embedded in series in said support by means of a zinc-cadmium alloy having a specific gravity not exceeding 8.3, and in which cadmium predominates.

3. A knitting element section for a knitting machine comprising a pressed metal support and a plurality of knitting elements embedded in series in said support by means of a zinc-cadmium alloy having a specific gravity not exceeding 8.3, and in which cadmium predominates, said support being perforated to secure the alloy firmly thereto.

EDWARD KINSELLA.
